[57] CLAIM

The ornamental design for a step rack, as shown and described.

DESCRIPTION

FIG. 1 is a front elevational view of a step rack showing my new design;

FIG. 2 is a top plan view of FIG. 1;

FIG. 3 is a rear elevational view of FIG. 1;

FIG. 4 is a left side elevational view of FIG. 1; the right side being a mirror image; and

FIG. 5 is a bottom view of FIG. 1;

FIG. 6 is a front elevational view of a second embodiment of my new design;

FIG. 7 is a top plan view of FIG. 6;

FIG. 8 is a rear elevational view of FIG. 6;

FIG. 9 is a left side elevational view of FIG. 6, the right side being a mirror image thereof; and

FIG. 10 is a bottom plan view of FIG. 6.
